MECHANICAL PRESS

Helmut Hecht, Goppingen, Germany, assignor to MAY-
Pressenbau Ltd., Schwabisch Gmund, Germany
Filed May 15, 1961, Ser. No. 110,200
3 Claims. (Cl. 78—39)

The present invention relates to a mechanical press having a table, which is preferably stationary, and a reciprocating ram operated by a crank or eccentric.

In quite a number of operations, for example in the cold deforming of metal it is unfavorable if the ram reciprocated by the crank or eccentric acts on the work piece treated as it were with a blow. On the contrary it is particularly advantageous in many cases, when the pressure applied by the ram after its impact on the work piece increases comparatively slowly to a maximum so that the material of the work piece has sufficient time for being deformed. In order to achieve this it has hitherto been of advantage to use for certain operations hydraulic presses, which make a less hard impact on the work piece and the pressure of which is controllable. On the other hand it has not been possible hitherto to develop mechanical presses in a manner favorable for these operations.

The present invention has the principal object of providing mechanical presses, for example crank- or eccentric-presses, the pressure of whose rams applied to the work pieces upon impact is smaller than the end pressure.

With this and other objects in view which will become apparent later from this specification and the accompanying drawings I provide a mechanical press comprising in combination: a table, a drive, a ram operatively connected to said drive and in operation reciprocated by said drive relative to said table, a presser member mounted in said ram opposite said table movably relative to said ram in the axial direction of the latter, abutments arranged on said ram limiting the movement of said presser member relative to said ram to a pre-determined length in either direction, hydraulic pressure fluid in operation contained in a hydraulic pressure chamber enclosed between the said ram and the said presser member resisting the receding of said presser member into said ram under the reaction of the pressing force applied by said presser member to a work piece resting against said table, and restoring the said presser member to its starting position upon said pressing force ceasing to act.

This arrangement acts as a damping device, by which the pressure upon impact of the ram on the work piece is reduced to a minimum and gradually increases to a predetermined value, so that the pressure applied to the work piece is not a hard blow but comparatively soft. Consequently the material to be deformed is not set in motion suddenly, but in a desirable manner gradually, whereby a more favorable and faultless flow of the material is achieved.

The arrangement may be made in such a manner that the reaction of the pressure fluid during the receding of the presser member under the pressing force is progressively increased by a control means, preferably up to the magnitude of the pressing force itself. This may for example be attained in that the pressure fluid displaced is forced through a throttle member, for example one or more restricted passages.

A particularly simple and reliable construction is achieved, when the control means has a passage the area of which gradually diminishes as the presser member recedes, namely if desired so far that this passage is completely or almost completely closed in the retracted end position of the said presser member. In this case the final maximum pressure of the ram is attained at the end of the receding movement of the presser member.

2

The control of the through-flow passage may for example be effected by a control element having the form of a projection matching the shape of the through-flow passage and attached to the end face of the presser member averted from the table. The shape of this projection depends accordingly on the shape of the through-flow passage. For example one component defining the through-flow passage may be conical, and then the said projection has likewise conveniently a conical shape. By suitably shaping the through-flow passage and the control element the pressure rise upon the receding of the presser member may in any case be influenced in a predetermined manner.

As a pressure fluid preferably a liquid is used, which acts directly on the presser member and flows through the control means, which liquid is subject to a gaseous pressure medium, so that similar to a liquid accumulator a movement of the liquid is possible either under the influence, or against the action, of the compressed gas, respectively.

Conveniently moreover a through-flow adjustment member operable from outside is provided on the ram by the aid of which the effective through-flow area is adjustable.

In order to vary the damping of the presser member attainable by the invention within wide limits it is convenient to provide, parallel to the main through-flow passage controlled by the presser member, at least one by-pass or secondary passage the area of which is adjustable by means of a throttle valve operable preferably from outside. By suitable choice of the cross section area of this by-pass it may for example be attained that the damping is a minimum when said by-pass is completely open since in this case practically the through-flow of the liquid through the main through-flow passage

is no longer decisive, since the liquid can flow off through the by-pass without difficulty, and the damping is in this case practically determined exclusively by the pressure of the compressed gas acting on the pressure fluid. By suitable adjustment of the throttle valve the characteristic of damping may be varied within wide limits in a manner desirable for the working operations.

Advantageously several by-passes may be arranged on a pitch circle at an equal angular spacing from one another in order thus to prevent an unequal pressure distribution with respect to the presser member.

If desired, on the presser member moreover a central member may be arranged, which penetrates through the main through-flow passage, so that the latter assumes an annular shape. By this arrangement it is made possible to provide centrally in the ram or presser member, respectively, some auxiliary members such as for example an ejector for ejecting the work piece.

These and other features of my said invention will be clearly understood from the following description of an embodiment and a modification thereof given by way of example with reference to the accompanying drawings, in which:

FIG. 1 is a front elevation of a first embodiment of a press according to the present invention;

FIG. 2 is a side elevation to FIG. 1;

FIG. 3 is a part-section on the line 3—3 of FIG. 2 on a larger scale;

FIG. 4 is a part-section corresponding to FIG. 3 of a modified embodiment of the present invention.

In the FIGS. 1-3 a press frame is denoted 10 as a whole, which has two side portions 11 and 12, and a table 13.

The drive of the press is effected by a drive motor (not shown) through a drive shaft 15 carrying a gear pinion 16 in mesh with a spur gear 17 mounted on a lay shaft 18 journalled in the lower portion of frame 10.

The drive shaft 15 is extended through and beyond the lower portion of the frame, and carries at its left hand side end in FIG. 1 a further gear pinion 20 in mesh with a further spur gear 21 which is likewise keyed to the lay shaft 18. On the outside of the drive gear 17 and 21, respectively, a crank pin 27 and 28, respectively, is arranged, on which a connecting rod 30 and 31, respectively, is articulated.

The two connecting rods 30 and 31 are arranged at both sides of the table on the side portions 11 and 12 in such a manner as to form a crank press having two uprights and a symmetrical drive on both sides. Above the table in a guide 35 a ram denoted 36 as a whole is slidably mounted, which has a projection 37 on each side (see FIGS. 3 and 4) on which an adjustment mechanism is arranged for the adjustment of the connecting rods 30 and 31. As will be seen in FIGS. 3 and 4, at each of the upper ends of the connecting rods 30 and 31 an adjustment member 40 is fitted which is screwed into a sleeve 41. This sleeve is mounted rotatable in the projections but is restrained longitudinally, and its rotation is effected by means of externally rotatable worms 42 in mesh with worm wheels arranged on the sleeves 41.

The details of the first embodiment of the ram according to the invention will now be explained in more detail with reference to FIG. 3.

The ram body 50 of the ram 36 is formed partly hollow internally and has an inner hub-like attachment boss 51 in which a pressure member 52 is arranged. The latter has a flange 53 which is arranged in a corresponding cylindrical recess 54 on the underside of the ram body 50 and can move therein in the axial direction a predetermined path, the upper abutment of this movement being formed by the end face 55 of said cylindrical recess 54, and the lower abutment by the head 56 of at least one screw 57 fixed in the ram body. As will be seen in FIG. 3, the presser member 52 may accordingly move a predetermined path a in the axial direction.

The presser member 52 has an inner cylindrical recess 60 serving for the attachment of tools. This recess is closed on top by a closure piece 61.

On the attachment boss 51 a cylindrical extension piece 62 is attached, which is sealed against the presser member 52 by the aid of gland rings 63. Between the upper end face of the closure piece 61 and the underside 65 of the extension piece 62 a cylindrical cavity 66 is formed, the axial height of which exceeds the path a .

The closure piece 61 carries in the middle a frustoconical control pin 68, which co-operates with a conical portion 69 of a through-flow passage 69/70, which includes moreover a cylindrical portion 70. On the extension piece 62 a cover 74 is arranged in such a manner that between the underside of the cover 74 and the face 75 of the extension piece 62 a cavity 76 is formed, which is in communication through connecting line 77 with a pressure vessel 78 to which a source of compressed gas (not shown in the drawing) is connected by means of a connector 79.

In the cover 74 moreover a control member 82 is provided in the form of an axially adjustable screw, which at its lower end has a conical control head 83 co-operating with the cylindrical portion 70 of the through-flow passage 69, 70.

The manner of functioning of the device described is as follows:

In a state of rest the presser member is in the position shown in FIG. 3 and accordingly contacts the abutment screw 57. Then the cavity 66 is entirely and the cavity 76 is partly filled with liquid, namely the latter up to a liquid level denoted 84. The compressed air contained in the pressure vessel 78 acts on this level so that under this action the liquid serving as the transmission medium constantly tends to move the presser member 52 into its lower position illustrated in FIG. 3.

When in the pressing operation a pressure is applied on the lower end face of the pressure member in the up-

ward direction the presser member is moved upward relative to the ram body 50 at a certain pressure exceeding the pressure of the compressed air, and thereby the liquid contained in the space 66 is forced through the passage 69, 70, which during the upward movement of the presser member is progressively reduced by the co-operation of the control pin 68 with the passage 69, 70, so that the pressure required for forcing the liquid through said passage progressively increases. In the uppermost position of the presser member, i.e. when the same has moved axially upward the amount a , the passage is completely or nearly completely closed, and in this position the presser member 52 is carried along immediately by the ram body 50, i.e. at this moment the action of the slidably proper member is completely abolished.

In FIG. 4 a second embodiment of the device according to the invention is illustrated.

Likewise in a ram body 85 here a presser member 86 is so arranged, that the latter may move a predetermined length a relative to the ram body. The presser member 86 is closed by a closure member 87 on which a central member 88 is attached which penetrates through this closure member. This central member has a conical control collar 89 which co-operates with a corresponding conical portion 90 of an annular extension 91 of the ram body.

The ram body is closed on top by a cover 92 through which penetrates the said central member 88 and which is sealed against this central member by means of a gland 93.

On the lower end of the central member 88 a lock nut 101 is screwed whereby the conical control collar 89 is firmly pressed against the closure member 87. On the upper end of the central member 88 a lock nut 102 is screwed. This nut 102 can rest on a cover plate 103 inserted in the cover 92.

In the aforesaid cover 92 an adjustment screw 94 is provided, which at its lower end (FIG. 4) is provided with a valve cone 95 cooperating with a valve seat 96 by a by-pass duct 97, which connects the chamber 98 with the chamber 99. Glands 104 on the closure member 87 seal the same off against the chamber 98.

The by-pass duct 97 may be varied in its effective cross-section area at will by adjusting the adjustment screw 94, in order to influence the damping characteristics of the damping device in the manner desired.

While I have described herein and illustrated in the accompanying drawing what may be considered a typical and particularly useful embodiment of my said invention I wish it to be understood that I do not limit myself to the particular details and dimensions described and illustrated; for obvious modifications will occur to a person skilled in the art.

What I claim as my invention and desire to secure by Letters Patent is:

1. A mechanical press comprising a press ram having a recess, means for reciprocating said press ram in an axial direction, a piston located in said recess axially movable relative to said press ram from an inoperative to an operating position leaving exposed a partial volume of said recess, a first stop means limiting the movement of said piston in said recess when in inoperative position, a second stop means limiting the movement of said piston in said recess when in operating position, said ram having a cavity containing a liquid under pressure, a passage connecting said partial volume and said cavity in said inoperative position of said piston, said passage including a part extending in said axial direction, the width of said part gradually diminishing in the direction of movement of said piston from said inoperative position to said operating position, throttling means rigidly fixed to said piston and in said inoperative position of said piston extending with lateral clearance into said part of said passage, said clearance being gradually reduced upon movement of said piston from said inoperative position to said operating position to increase the action of said throttling means.

2. A mechanical press comprising a press ram having a recess, means for reciprocating said press ram in an axial direction, a piston located in said recess axially movable relative to said press ram from an inoperative to an operating position leaving exposed a partial volume of said recess, a first stop means limiting the movement of said piston in said recess when in inoperative position, a second stop means limiting the movement of said piston in said recess when in operating position, said ram having a cavity containing a liquid under pressure, a passage connecting said partial volume and said cavity in said inoperative position of said piston, said passage including a part extending in said axial direction, the width of said part gradually diminishing in the direction of movement of said piston from said inoperative position to said operating position, throttling means rigidly fixed to said piston and in said inoperative position of said piston extending with lateral clearance into said part of said passage, said clearance being gradually reduced upon movement of said piston from said inoperative position to said operating position to increase the action of said throttling means, said partial volume, said passage and said cavity containing a liquid forming a level of liquid in said cavity, and supply means for pneumatic pressure connected to said cavity to resiliently charge 25 said level of liquid by said pneumatic pressure.

3. A mechanical press comprising a press ram having a recess, means for reciprocating said press ram in an axial direction, a partition in said ram dividing said recess into a first and a second pressure chamber, a cylindrical tool support in said first chamber axially movable relative to said press ram from an inoperative to an operating position, sealing means upon said tool support co- 30

operating with the wall of said first pressure chamber to seal the latter when said tool support is moved relative to said ram, a first stop means limiting the movement of said tool support in said ram when in inoperative position, a second stop means limiting the movement of said tool support in said ram when in operating position, a passage connecting said two chambers in said inoperative position, said passage including a part extending in said axial direction, the width of said part gradually diminishing in the direction of movement of said piston from said inoperative position to said operating position, throttling means rigidly fixed to said piston and in said inoperative position of said piston extending with lateral clearance into said part of said passage, said clearance being gradually reduced upon movement of said piston from said inoperative position to said operating position to increase the action of said throttling means, said chambers and said passage containing a liquid forming a level of liquid in said second pressure chamber, and pneumatic pressure supply means connected to said second pressure chamber to resiliently charge said level of liquid by said pneumatic pressure.
